Specification of Letters Patent.

Patented Sept. 9, 1913.

Application filed July 29, 1907. Serial No. 385,956.

To all whom it may concern:

Be it known that I, HOWARD D. COLMAN, a citizen of the United States, residing at Rockford, in the county of Winnebago and State of Illinois, have invented certain new and useful Improvements in Knotters, of which the following is a specification.

One of the objects of this invention is to produce a knot-tying mechanism adapted to tie knots in worsted and other wiry yarns. When such yarns are coiled or looped by knot-tying mechanisms heretofore produced, to form a knot, the coils tend to spring open, and owing to the limited amount of force 10 that can be exerted by such mechanisms for tightening the knot, a loose knot is formed which is liable to work still looser and may fail altogether. This difficulty in tying wiry yarns I remedy by giving the tying bill of 15 the machine an additional revolution after the loop is formed, thereby coiling the looped threads upon themselves previous to drawing said threads through the loop upon the tying bill. I find that a knot thus formed 20 will not work loose or slide upon the threads.

The present embodiment of my invention is adapted to be mounted upon the hand of the operator, and is designed especially for use in textile mills by the attendants upon 25 the spooler frames. When a bobbin is emptied, the operative substitutes a new bobbin, stops the rotation of the corresponding spool by laying her hand upon the top thereof, and with the other hand places the 30 end of the thread from the bobbin and the end of the thread from the spool in proper relation to the knot-tying mechanism for the tying of a knot. In certain of the knot-tying implements which I have heretofore 35 produced the mechanism is digitally actuated.

It is one of the objects of the present invention to provide means for actuating the knot-tying mechanism with power derived 40 from the machine tended by the user of the implement. In the device herein shown means is provided for obtaining a driving engagement with the rotating spool next to the spool stopped by the operative as before 45 described.

The invention also relates to the other improvements in knot-tying mechanisms hereinafter set forth.

In the accompanying drawings, Figure 1

is a side view of one embodiment of my invention, illustrating the implement as mounted upon the hand of the operative and showing the method of operation and the means for actuating the mechanism. Fig. 2 is a partial side elevation of the implement 55 viewed from the side opposite to that seen in Fig. 1. Fig. 3 is a fragmental forward end view of the implement. Fig. 4 is a partial rear end view thereof. Fig. 5 is a top plan view of the device. Fig. 6 is a detail 60 view of the clamp arm. Fig. 7 is a detail 65 view of the tying bill showing the cam barrel in longitudinal central section. Fig. 8 is a transverse section through the tying bill and cam barrel taken on the plane of dotted 70 line 88 of Fig. 7. Fig. 9 illustrates a means for stopping the mechanism at the end of each cycle of operation. Fig. 10 is a flat development of the periphery of the actuating cam cylinder. Figs. 11 to 18 are views 75 in series illustrating the knot-tying operation. Fig. 19 is a diagrammatic view of the knot tied by the machine.

In the embodiment selected for illustration the mechanism is mounted upon a plate 80 1 to which a strap 2 is secured in any suitable manner, said strap being adapted to be buckled around the hand of the operator as shown in Fig. 1. The supporting frame 3 is rigidly secured to the plate 1. A main 85 shaft 4 is rotatably mounted in said supporting frame, and carries at its rear end a sprocket wheel 5. To the plate 1 is fixed a bracket 6 Figs. 1 and 4 in which is rotatably mounted a shaft 7 bearing a sprocket 90 wheel 8 and drive wheel 9. Said drive wheel is so located with reference to the strap 2 and the distance between the spools upon the spooling frames in common use, as to lie in position to contact the upper head 95 of the spool next to the one stopped by the operative when she is about to tie on the thread from a new bobbin. Preferably the driving wheel 9 or its peripheral portion consists of material adapted to provide good 100 driving contact with the spool, such as rubber or leather. A sprocket chain 10 extends over the sprocket wheels 5 and 8.

The forward end of the shaft 4 is flattened and bent at substantially a right angle to 105 form the portion 11 of the tying bill 12, a pivot pin 13 being fixed in said portion. A portion 14 of the tying bill 12, commonly

termed the bill spring, is made removable for purposes of renewal. It is secured to the shaft 4 by means of the sleeve 15. The movable jaw 16 of the tying bill is pivotally mounted upon the pivot pin 13 and is provided with a cam wing 17 adapted, in the rotation of the tying bill, to engage the interior walls of a cam barrel 18 rigidly mounted in the supporting frame. When the shaft 4 is rotated, the cam wing 17, engaging the interior walls of the cam barrel 18, is swung upon its pivot 13, thereby swinging the shearing and clamping jaw 16 and opening and closing the tying bill.

15 A stripper arm 19 having a hook 20 at its forward end, is pivotally mounted in the supporting frame at 21 by means of the attaching lugs 22 and 23. (Figs. 3, 4 and 5). A lever 24 is pivotally mounted at a point 20 between its ends in the frame upon a pivot pin 25. (Fig. 6.) One end of said lever is pivotally connected with one end of a clamp arm 26, the opposite end of which clamp arm has two upwardly-extending fingers 27 between which the stripper arm 19 is slidably mounted. The means herein shown for moving the stripper arm 19 and the clamp arm 26 comprises a cam cylinder 28 mounted upon a shaft 29 in the supporting frame. 25 A gear wheel 30 formed integral with or otherwise suitably secured to the cam cylinder 28 meshes with a pinion 31 fixed upon the main shaft 4. In the cam cylinder 28 are formed two cam grooves 32 and 33. A 30 roller 34 mounted upon the under side of the lever 24 lies within the cam groove 33. A rock shaft 35 mounted in the supporting frame has at its lower end an arm 36 provided with a roller 37 adapted to travel in the cam groove 32. Upon the upper end of the rock shaft 35 is an arm 38 connected with the stripper arm 19 by means of the link 39 (Fig. 5). The stripper arm 19 is arranged to swing upon the axis 21 from the position shown in Fig. 3 outwardly to the position illustrated in the perspective view Fig. 17.

35 A thread guide 40, hooked at its forward end, is slidably mounted in a guide-way 41 (Fig. 3) in the supporting frame, to slide in a direction substantially parallel with the axis of the tying bill. This movement is given it by means of the lever 24, one arm of said lever engaging in a notch 42 (Fig. 1) in the rear end of the thread guide 40.

40 Means is provided for stopping the mechanism at the end of each complete cycle of operation, in order that the tying bill, thread guide, stripper arm and clamp arm 60 shall be in proper position for the next operation. Said means comprises a pin 43 (Fig. 9) fixed to the spur gear 30 and a stud 44 fixed to a lever 45 pivotally mounted at 46 in the supporting frame. A coiled spring 47 tends to move the stud 44 into the path

of the pin 43. The pivotal movement of the lever 45 in one direction is limited by the impingement of a stop 48 upon the adjacent portion of the supporting frame, and the movement of said lever in the opposite direction is limited by the end 49 (Fig. 3) of said lever striking against the portion 50 of the frame. An arm 51 fixed to the lever 45 extends into position to be moved by the thumb of the hand upon which the implement is mounted, for lifting the stud 44 out of the path of the pin 43.

When in use, the implement is mounted upon the left hand of the operative, as shown in Fig. 1. Assuming the mechanism to stand in the position shown in Figs. 1 to 5, the operation is as follows: When the thread running to any spool is exhausted, the operative substitutes a new bobbin, stops the spool by laying her left hand upon the top thereof, the drive wheel 9 lying directly above the spool next to the left, and with her right hand draws the ends of the two threads across the stripper arm 19, the tying bill 12 and the thread guide 40, as indicated in Figs. 1 and 11, the threads lying in the hooks of said stripper arm and thread guide, and directly behind the tying bill. Tilting the implement slightly to bring the wheel 9 into driving contact with the spool below it, the operative releases the mechanism to action by raising the arm 51 with her thumb. The operation of the tying bill is substantially the same as that of the tying bill illustrated in Patent No. 755,110, issued to me on March 22, 1904, except that the tying bill of the present machine makes an additional revolution before the threads are received in the open bill. Referring to Fig. 11: As the tying bill turns toward the left into the position shown in Fig. 12 the bill is closed by the action of the cam barrel 18 on the cam wing 17, and the bill lies across the threads as shown in Fig. 12. The first three-fourths of a revolution of the tying bill from the initial position loops the threads about said bill, as shown in Fig. 13. During the next complete revolution of the bill, the threads are coiled upon themselves at one side of the loop upon the bill, the clamp arm advances to clamp the threads in the hook 20, and the thread guide 40 moves rearwardly to bring the threads at that side of the tying bill into the path of the open bill (Fig. 15). During the succeeding three-fourths of a revolution, the threads are clamped in the tying bill, the waste ends clipped off by the clamping and shearing jaw 16, the loop upon the bill pulled over said clamped ends and the completed knot 125 tightened and pulled from the tying bill by a pivotal movement of the stripper arm 19, and the thread guide 40 returned to its forward position. The remaining half-revolution restores the tying bill, the stripper arm 130

and the clamp arm to the initial position, the withdrawal of the fingers 27 of the clamp arm from the hook 20 releasing the united thread-ends. The mechanism is stopped in the initial position by the engagement of the pin 43 with the stud 44, the gear 30 making one revolution to each complete cycle of movement.

The operation may be summarized as follows: During the first revolution of the tying bill, the threads are looped about said bill. During the second revolution the threads are coiled upon themselves and the strands received in the open bill. During the third revolution the strands are sheared and clamped, the loops pulled off the bill and drawn tight on the threads, and the ends pulled out of the bill. The coiling of the threads upon themselves prior to their being drawn through the loop upon the tying bill prevents the coils of the knot from springing apart or sliding when tension is placed upon the threads. In order that the implement may be used for tying the ordinary spooler's knot, means is provided for changing the cycle of movement to begin with the second revolution of the tying bill. The pin 43 is formed upon a screw 52 adapted to be placed in either of two threaded holes 53 and 54. When placed in hole 54 the first revolution winds the threads about the tying bill as shown in Fig. 13 and the guide 40 places the threads so that the open bill takes them as shown in Fig. 15. The second revolution pulls the ends through the loop on the tying bill and tightens and strips the knot, the third revolution occurring after the completion of the knot as shown in Figs. 16 and 17.

I realize that various embodiments of the invention are possible, and therefore would have it understood that I do not limit myself to the arrangement of parts and the details of construction herein shown and described.

I claim as my invention:

1. A knot-tying mechanism comprising a rotatable tying bill, means for opening and closing said tying bill, and means for moving the threads into the path of the open tying bill.

2. A knot-tying mechanism comprising a rotatable tying bill, means for rotating said bill through three revolutions, and means for moving the threads into the path of the tying bill after the completion of one revolution.

3. A knot-tying mechanism comprising a rotatable tying bill arranged to be opened and closed, and means for supporting threads in position for action thereon by the closed bill, a portion of said supporting means being movable to place the threads in position for action thereon by the open bill.

4. A knot-tying mechanism comprising a rotatable tying bill arranged to be opened

and closed, a stationary thread guide at one side of said bill, a thread guide at the opposite side of said bill, said guides being arranged to support threads in position for action thereon by the closed bill, and means for moving the second mentioned guide transversely of the plane of rotation of the tying bill to place the threads in position for action thereon by the open bill.

5. A knot-tying mechanism comprising a tying bill, means for rotating said tying bill, a thread clamp comprising a clamp arm, a thread guide, and means for simultaneously moving said clamp arm and said thread guide.

6. A knot-tying mechanism comprising a tying bill, means for rotating said tying bill, a thread clamp comprising a clamp arm, a thread guide, a lever connected at its opposite ends with said clamp arm and said thread guide, and means for oscillating said lever.

7. A knot-tying mechanism comprising a main shaft, means for rotating said main shaft, a tying bill rotated by said main shaft, a thread clamp, and a cam and connections for actuating said thread clamp, said cam being driven by said main shaft.

8. A knot-tying mechanism comprising a main shaft, means for rotating said shaft, a tying bill rotated by said shaft, a rotatably mounted cam cylinder, a gear connection between said cylinder and said shaft, and a thread clamp operatively connected with said cam cylinder.

9. A knot-tying mechanism comprising a main shaft, means for rotating said shaft, a tying bill, a stripper arm, a clamp arm, a cam cylinder driven by said shaft, and connections between said cam cylinder and said stripper arm and clamp arm for moving said arms.

10. A knot-tying mechanism comprising a main shaft, means for rotating said shaft, a tying bill, a stripper arm, a clamp arm, a thread guide, a cam cylinder having a gear connection with said shaft, a lever connected at its ends with said clamp arm and said thread guide and arranged to be moved by said cam cylinder, and a connection between said strip or arm and said cam cylinder for moving said arm.

11. A knot-tying mechanism comprising a tying bill and coöperating parts, and means for stopping said tying bill at the end of its third revolution.

12. A knot-tying mechanism comprising means for stopping the parts in the initial position, and a member adapted to be engaged by the operator for operating said stopping means.

13. A knot-tying mechanism comprising a tying bill and coöperating parts, and adjustable means for stopping the rotation of said tying bill.

14. A knot-tying mechanism comprising members to engage the threads, a cam cylinder and connections for actuating said members, an adjustable stop on said cylinder, and a coöperating stop.

15. The combination of a knot-tying mechanism, means to support said mechanism, said means being arranged to engage the hand of the operator, a drive wheel mounted 10 on said supporting means in such position that when the hand supporting the mechanism is on one spool said wheel is in engagement with the next adjacent spool, and a driving connection between said wheel and 15 said mechanism.

16. The combination, with a textile machine, of a strap for securing said machine to the hand of the operator; a driving wheel mounted on said strap; a sprocket wheel

fixed with relation to said driving wheel; 20 a sprocket wheel connected to said machine; and a chain running over said sprocket wheels.

17. The combination of a knot-tying mechanism, a strap to encircle the hand of 25 the operator, said mechanism being attached to that portion of the strap which passes across the back of the hand, a drive wheel supported adjacent to said strap whereby when the operator lays his hand on a spool 30 of a spooler frame said wheel will contact the next adjacent spool, and a driving connection between said wheel and said mechanism.

HOWARD D. COLMAN.
